HIGH FREQUENCY NETWORK

Bernardus Dominicus Hubertus Tellegen, Eindhoven, Netherlands, assignor to Radio Corporation of America, a corporation of Delaware

Application October 28, 1931, Serial No. 571,510
In the Netherlands April 25, 1931

3 Claims. (Cl. 178—44)

The invention relates to a tunable oscillatory system consisting of capacitively coupled circuits, and it has for its object to provide a tunable system in which the coupling varies with the tuning 5 in a predetermined desired manner.

According to the invention, in order to attain this purpose use is made of a system comprising a combination of a capacitive coupling whose strength increases with the frequency, and a 10 capacitive coupling whose strength decreases with the frequency. A judicious choice of the relative strength of the two couplings allows of keeping the coupling substantially constant for the whole region to which the system can be tuned. On 15 the other hand, the strength of the coupling may be caused to vary with the tuning in a predetermined manner if such variation should be desired.

The novel features which I believe to be characteristic of my invention are set forth in particularity in the appended claims, the invention itself, however, as to both its organization and method of operation will best be understood by reference to the following description taken in connection with 20 the drawings in which I have indicated diagrammatically several circuit arrangements whereby my invention may be carried into effect.

The invention will hereinafter be explained 25 more fully with reference to the drawings which represent some explanatory figures and, by way of example, some embodiments of the invention.

Figs. 1 and 2 serve to elucidate the following 30 considerations on capacitive coupling in general, and,

Figs. 3 to 9 inclusive represent by way of example, some embodiments of the system according to the invention.

In Fig. 1, two oscillatory circuits $L_1 C_1$ and $L_2 C_2$ are coupled to one another by means of a condenser C_3 . If the capacity C_3 is considerably 35 smaller than that of C_1 and C_2 , it can be theoretically shown that the coupling factor k may be represented by the expression:

$$k = \frac{C_3}{\sqrt{C_1 C_2}}$$

This expression is obtained by neglecting in the exact formula C_3 relative to C_1 and C_2 .

If the two circuits are tuned to the same frequency, the expression for k may be written with the aid of the relation between the resonance frequency ω and the electrical magnitudes of the two circuits as follows:

$$k = \omega^2 C_3 \sqrt{L_1 L_2}$$

If the tuning is effected with the aid of the variable condensers C_1 , C_2 and if L_1 and L_2 remain unaltered, the coupling factor consequently depends on the frequency, which means that the coupling factor increases when the frequency increases. 5

Fig. 2 represents a circuit arrangement with which the coupling factor decreases with the frequency. In this arrangement the coupling is brought about by means of a condenser C_4 which is assumed to have a large capacity relative to the variable capacities C_1 and C_2 . In this case the coupling factor k has been found to be equal to: 10

$$k = \frac{1}{\omega^2 C_4 \sqrt{L_1 L_2}}$$

Figs. 1 and 2 consequently represent types of coupling with strongly different frequency dependency. According to the invention, in order to obtain the desired variation of the coupling factor with the frequency, the two kinds of coupling are combined. A judicious choice of the strength of the different couplings allows in this case of obtaining a constant coupling, or a coupling which varies with the frequency in a predetermined manner. 20 25

A first embodiment of a circuit arrangement with such combined coupling is represented, by way of example, in Fig. 3. By reason of the conditions above assumed with respect to the values of C_4 and C_3 relative to C_1 and C_2 , the total coupling factor may be assumed to be the total amount of the two coupling factors in the cases of Figs. 1 and 2. The coupling factor in the system according to Fig. 3 consequently contains two 30 35 terms of which one increases with the frequency whereas the other decreases with the frequency.

A judicious choice of the values C_3 and C_4 renders it possible to obtain, for example, that over the whole region of the tuning the coupling factor varies only slightly. A source of signal energy S may be considered coupled to L_1 , while a utilization circuit U is coupled to coil L_2 . 40

Fig. 4 represents a system in which the coupling factor is independent of the frequency. If in this system C_5 is considerably smaller than C_1 and C_2 , and if C_6 is considerably larger, the following expression for the coupling factor is found: 45

$$k = \frac{C_5}{C_6} \sqrt{\frac{L_2}{L_1}}$$

Fig. 5 represents a circuit arrangement of exactly the same kind as that of Fig. 4, which however, is made symmetrical by adding two condensers C_6 and C_7 of which the former is large 50 55

relative to the tuning capacities, whereas the latter is small relative to these capacities. The coupling factor of this system may be represented as follows:

$$5 \quad k = \frac{C_5}{C_6} \sqrt{\frac{L_2}{L_1}} + \frac{C_7}{C_8} \sqrt{\frac{L_1}{L_2}}$$

In this case, too, the coupling is consequently independent of the tuning frequency.

- 10 The most general form of the coupling factor which can be obtained in the manner indicated with the aid of fixed capacities is:

$$k = a\omega^2 + \frac{b}{\omega^2} + c$$

15 The coefficients a , b and c occurring in this expression, may have different signs, and their values can be controlled by the choice of the values of the coupling capacities.

- 20 If in Fig. 3 L_1 and C_1 or L_2 and C_2 are interchanged, the two couplings counteract each other, and the expression for the coupling factor may be written as follows:

$$25 \quad k = \omega^2 C_3 \sqrt{L_1 L_2} - \frac{1}{\omega^2 C_4 \sqrt{L_1 L_2}}$$

The circuit arrangement shown in Fig. 5 also gives with the interchange of L_1 and C_1 or L_2 and C_2 an inversion of the sign of one of the terms of 30 which consists the expression for the coupling factor. It is evident that thus the course of the coupling factor can be varied in various ways.

35 Fig. 6 represents a system with three small capacities C_3 , C_5 , C_7 and three large capacities C_4 , C_6 , C_8 . This circuit arrangement may be considered to be produced by combining Fig. 5 with Figs. 1 and 2. The expression for the coupling factor is found in this case:

$$40 \quad k = \omega^2 C_3 \sqrt{L_1 L_2} + \frac{1}{\omega^2 C_4 \sqrt{L_1 L_2}} + \frac{C_5}{C_6} \sqrt{\frac{L_2}{L_1}} + \frac{C_7}{C_8} \sqrt{\frac{L_1}{L_2}}$$

The number of fixed condensers may be much increased but one always obtains a coupling factor of the general type as above indicated.

45 An increase of the number of condensers is consequently practically of no consequence. The systems obtained always have coupling factors of the general type above referred to and besides a term which is independent of the frequency there 50 occurs a term which decreases with the frequency, and a term which increases with the frequency.

55 Fig. 7 represents, by way of example, a circuit arrangement in which the condenser C_3 has a slight capacity which is smaller than those of the tuning condensers C_1 and C_2 while C_9 is of the same order of magnitude as C_1 and C_2 . With this arrangement one obtains a coupling factor of the type

$$k = a\omega^2 - b$$

60 in which a and b are positive constants.

In Fig. 8, C_4 is considerably larger than C_1 and C_2 , whereas C_{10} is of the same order of magnitude as C_1 and C_2 . The coupling factor is now of the 65 type

$$k = \frac{a}{\omega^2} - b$$

Finally, in Fig. 9 the capacities C_9 and C_{11} are 70 of the same order of magnitude as the tuning capacities whereas C_3 is very small. The coupling factor is now of the type

$$k = \frac{a}{\omega^2} - b + c\omega^2$$

75 It will be understood that in each of the above

figures the condensers C_1 and C_2 may be arranged for simultaneously and similarly tuning the oscillatory circuits with which they are associated. They can obviously be employed between tubes in a radio frequency amplifier, or between an antenna and a tube in a receiver. Further, while I have indicated and described several systems for carrying my invention into effect, it will be apparent to one skilled in the art that my invention is by no means limited to the particular organizations shown and described, but that many modifications may be made without departing from the scope of my invention as set forth in the appended claims.

What is claimed is:

1. A high frequency coupling network, adapted for coupling a preceding source of high frequency signal energy to a following high frequency load circuit, said network comprising a pair of resonant circuits each including a coil and a variable tuning condenser, one of said coils being magnetically coupled to the source and the other being magnetically coupled to said load circuit, said variable condensers being adapted for simultaneously and similarly tuning said resonant circuits to a desired signal frequency, and means, providing a purely capacitative coupling between the resonant circuits which is independent of the tuning of the latter, comprising a fixed condenser, considerably larger than said variable condensers, 30 connected in shunt with the coil and variable condenser in one of said resonant circuits, and a fixed condenser, considerably smaller than said variable condensers, connected between points of the same high frequency potential of the variable 35 condenser, of the other resonant circuit, and the said shunt fixed condenser.

2. A high frequency coupling network, adapted for coupling a preceding source of high frequency signal energy to a following high frequency load circuit, said network comprising a

40 pair of resonant circuits each including a coil and a variable tuning condenser, one of said coils being magnetically coupled to the source and the other being magnetically coupled to said load circuit, said variable condensers being adapted for simultaneously and similarly tuning said resonant circuits to a desired signal frequency, and means, providing a purely capacitative coupling between the resonant circuits which is independent of the tuning of the latter, comprising a fixed condenser, considerably larger than said variable condensers, 45 connected in shunt with the coil and variable condenser in one of said resonant circuits, and a fixed condenser, considerably smaller than said variable condensers, connected between points of the same high frequency potential of the variable 50 condenser, of the other resonant circuit, and the said shunt fixed condenser.

3. A high frequency coupling network, adapted for coupling a preceding source of high frequency signal energy to a following high frequency load circuit, said network comprising a pair of resonant circuits each including a coil and a variable tuning condenser, one of said coils being magnetically coupled to the source and the other being magnetically coupled to said load 55 circuit, said variable condensers being adapted for simultaneously and similarly tuning said resonant circuits to a desired signal frequency, and means, providing a purely capacitative coupling between the resonant circuits which is independent of the tuning of the latter, comprising a fixed condenser, considerably larger than said variable condensers, 60 connected in shunt with the coil and variable condenser in one of said resonant circuits, and a fixed condenser, considerably smaller than said variable condensers, connected between points of the same high frequency potential of the variable condenser, of the other resonant circuit, and the said shunt fixed condenser,

65 a second fixed condenser, larger than the magnitudes of the said variable condensers, in shunt with the coil and variable condenser of said last named resonant circuit, and a fixed condenser, smaller than said variable condensers, connected between points of the same high frequency potential of the variable condenser of said one resonant circuit and the said second shunt condenser.

70 3. A tunable high frequency transmission network, adapted to couple a source of signal energy to a load circuit, comprising a pair of resonant circuits each including a coil and a variable tuning condenser in series, said tuning condensers being adapted to tune said network to a common frequency of a desired frequency range, a first 75

5 Large fixed condenser connected in series with one tuning condenser, a second large fixed condenser connected in series with the other tuning condenser and a third large fixed condenser connected on one side to a point common to both coils and on the other side to a point common to said first and second large condensers, a small fixed condenser in series between each coil of one resonant circuit and the tuning condenser of the other resonant

circuit, another small fixed condenser connected between points of the same signal potential of both coils, said three large condensers being each larger than said tuning condensers, and each of said small condensers being smaller than said tuning condensers. 5
